UNITED STATES PATENT OFFICE.

LEONARD SAWYER, OF MERRIMAC, MASSACHUSETTS.

TOP-PROP FOR CARRIAGES.

SPECIFICATION forming part of Letters Patent No. 248,887, dated November 1, 1881.

Application filed September 17, 1881. (No model.)

To all whom it may concern:

Be it known that I, LEONARD SAWYER, of Merrimac, county of Essex, State of Massachusetts, have invented a certain new and useful Improvement in Top-Props for Carriages, of which the following is a description sufficiently full, clear, and exact to enable any person skilled in the art or science to which my invention appertains to make and use the same, reference being had to the accompanying drawings, forming a part of this specification, in which—

Figure 1 is an isometrical perspective view; Fig. 2, a vertical longitudinal section; and Fig. 3, a section of the retaining-thimble.

Like letters indicate corresponding parts in the different figures of the drawings.

My present invention relates to that class of top-props in which the body is detachable from the plate, being designed as an improvement on the prop secured to me by Letters Patent of the United States numbered 163,812, bearing date May 25, 1875; and it consists in a novel construction and arrangement of parts, as hereinafter more fully set forth and claimed, by which a more effective device of this character is produced than is now in ordinary use.

In the drawings, A represents the plate; B, the body; C, the nut; D, the thimble, and E the washers.

The body B is exteriorly threaded at its inner end to form the left-hand screw F, which fits a corresponding female screw in the stud or hub G, projecting outwardly from the plate A.

The thimble D has a hole in its top or outer end, through which the body B passes, and is provided with a rabbet or shoulder, H, which engages with a boss or projection, I, on the body A when the thimble is turned down into position.

The stud G is exteriorly threaded to form a right-hand screw, which fits a corresponding female screw, J, in the thimble D.

The body B is grooved or channeled longitudinally at K to receive corresponding projections m m on the washers E, between which washers the braces (not shown) are arranged when the prop is in use.

The boss I of the body B, when the body is screwed into the stud G to its fullest extent, 50 rests on the outer end of the stud, the lower or inner end of the screw F being then nearly flush with the inner face of the plate A.

The thimble D is shortened at its lower or inner end, so that when it is fully turned down 55 to bring the shoulder H into contact with the boss I there will be a space between the thimble and outer face of the plate A into which space the leather forming the covering of the top of the carriage projects, the raw edge of 60 the same around the stud G being covered by the lower or inner end of the thimble.

A difficulty has heretofore existed in props of this description, arising from the loosening or unscrewing of the body B in the stud G, 65 caused by the strain or action of the braces on the body. This difficulty or imperfection is fully obviated by threading the interior and exterior screws of the stud G in opposite directions—that is to say, making them respectively left and right hand screws—so that when the body B is in position, as shown, and the thimble D fully turned down, the unscrewing of the body cannot take place, accidentally or otherwise, without first unscrewing the thimble, as the same would operate to turn the thimble more firmly down onto the boss I.

It will be obvious that the stud G may be provided with an exterior left-hand screw and an interior right-hand screw in place of those 80 shown, the thimble D and body B being respectively threaded to correspond therewith, without departing from the spirit of my invention.

Having thus explained my improvement, 85 what I claim is—

In a top-prop for carriages, the body B, provided with the left-hand screw F, and thimble D, provided with the right-hand screw J, in combination with the stud G, properly threaded to receive the same, substantially as specified.

LEONARD SAWYER.
